Howard M. Cohn(57) **CLAIM**

The ornamental design for a hand truck as shown and described.

DESCRIPTION

FIG. 1 is a front, top and left side perspective view of a hand truck showing my new design, the handlebar being folded;
FIG. 2 is a front elevation view thereof;
FIG. 3 is a rear elevation view thereof;
FIG. 4 is a left side elevation view thereof, the right side elevation view being a mirror image of the left side elevation view;
FIG. 5 is a top plan view thereof;
FIG. 6 is a bottom plan view thereof;
FIG. 7 is a rear, bottom and right side perspective view of the hand truck, the wheels being folded in condition of storage; and,
FIG. 8 is another front, top and left side perspective view of the hand truck, the handlebar being fully extended in an unfolded position, in condition of use.
The broken lines in the drawings illustrate portions of the hand truck that form no part of the claimed design.
